PORTABLE KILN

Frederick W. Fuger, Grosse Pointe, Mich.

Application April 30, 1952, Serial No. 285,205

2 Claims. (Cl. 25—132)

1

The object of my improvement is to produce a kiln suitable for firing small objects such as figurines, trays, vases, etc. The kilns contemplated by me are to be small and portable, that is, adapted to be transferred from place to place as required.

A more specific object of my invention is to provide a kiln composed of two units, namely, a base which is provided with means to produce heat needed for firing and a removable dome fitting over the base.

A further object of my improvement is to produce a dome of suitable clay while in a plastic condition and to have it fired into a monolithic structure preferably by the same heat-producing means which are to be utilized in firing any objects within the dome resting on said base.

Finally, my object is to provide a kiln of simple construction, economical in cost and fully practical for the purposes above specified.

I shall now describe my invention with reference to the accompanying drawing in which:

Fig. 1 is a vertical sectional view of my kiln including a base and a removable dome resting thereon;

Fig. 2 is a sectional view of the dome on line 2—2 of Fig. 1;

Fig. 3 is a sectional view of the base of the kiln on line 3—3 of Fig. 1;

Fig. 4 is a sectional view of the base on line 4—4 of Fig. 1, the view disclosing the location of heat-producing means within said base;

Fig. 5 is a perspective view reduced in size of the dome as it appears from outside.

Similar numerals refer to similar parts throughout the several views.

The kiln shown in the drawings is circular in shape. While this is a preferred form thereof, it is not critical and may be modified as desired. The base, which is generally identified by numeral 10, may be made of a suitable refractory concrete and is provided with a centrally-located well 11 which is open at the top.

Disposed within the well, in a spaced relation to its bottom 12, is a ring-shaped gas burner 13 made of a pipe provided with a plurality of holes 14 for release of a gaseous fuel to be supplied from an outside source by a pipe 15.

Resting upon the rim portion 16 of the well is a grating 17 affording means for support of items which are to be fired within the kiln. A duct for intake of air from outside the base to sustain burning of fuel within the kiln is marked 18.

At the top the base is of a reduced diameter,

2

resulting in the formation of a thin annular wall 19 and of an outwardly-disposed ledge 20.

Now I shall refer to the dome or cover, generally identified by numeral 21. The dome, made in the form of a shell, is open at the bottom, the diameter of said shell at the bottom being substantially equal to that of the base. The wall of the dome at the bottom is of a thickness permitting said dome to rest on ledge 20, while the annular wall 19 at the top of base 10 fits snugly into the interior of said dome, as best shown in Fig. 1.

A member of this type may be produced on a potter's wheel, shaped upon a dome-shaped form, or may be made by means of a mold of a suitable plastic material.

Once fired the dome is to be dried and dehydrated by application of heat from such source as infra-red lights, whereupon the dome may be fired or baked into a hard monolithic structure.

The dome shown in the drawing is provided on its inner surface with vertical ribs 22 for the purpose of imparting to the structure greater rigidity while it is still in its plastic condition and a greater strength in its finished stage. The feature, however, is only suggestive and not indispensable.

Located within the top of the dome is a flue 23 to provide an outlet for combustion gases generated within the base portion of the kiln.

Two lateral ears 24 serve as means to support the dome manually while it is being seated upon said ledge 20 or to remove the dome from the base.

In order that the progress of firing objects within the dome may be viewed from outside while the dome is seated upon base 10, I have provided said dome with a window 25, the window being set in the wall of the dome preferably close to its bottom, as shown in the drawing.

Once the dome has been dried to acquire sufficient rigidity for safe handling, the objects to be fired may be placed upon the grating 17, whereupon gas may be ignited at the burner 13 and dome 21 may be placed upon ledge 20, as shown in Fig. 1. The heat which is required to bake the objects within the dome will also fire the body of the dome itself. When the objects within the kiln are to be removed therefrom, the dome is simply lifted off by means of said ears 24 to permit access to said objects.

After the dome has been baked into a stone-like consistency by the first firing of the objects within said dome, the kiln as a whole may be used time and again to fire other objects.

After having described my improvement, what I wish to claim is as follows:

1. A portable kiln comprising a base provided with a well therein, the well being open at the top, a heat-producing unit within the well, a grating resting upon parts of the base at a level above the heat-producing unit, an air duct below said unit to admit air from outside the base, a dome of monolithic construction to fit over and to be supported by the top of the base, and a flue within the top of the dome to release combustion gases from within said dome, said dome being adapted to be lifted from the top of the base when desired.

2. A portable kiln comprising a circular base 15 provided with a centrally-located well, a source of heat within the well, a duct to supply air from outside the base to said well, a grating over said source of heat, the grating being supported by a rim portion of the well, the upper portion of the 20 base forming an annular wall of a reduced diam-

eter, leaving a horizontal ledge thereabout, a shell-like dome of monolithic construction, the dome having a bottom resting on said ledge, and encircling said wall, and a flue at the top of the dome to release gases from within the kiln, the dome being removable from said base for placing objects to be fired within the kiln and for removal of said objects after firing.

FREDERICK W. FUGER.
